UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 14,416, dated November 13, 1883.
Application filed August 23, 1883. Term of patent 3½ years.

To all whom it may concern:

Be it known that I, CATHERINE O'HARA, of the city, county, and State of New York, have invented and produced a new and original Design for a Pattern of a Lady's Polonaise, numbered 8,832; and I do hereby declare that the engraved prints accompanying this specification convey to any one accustomed to using paper patterns a clear understanding of how a garment made up by the pattern will appear.

The design combines a closely-fitted front buttoning part of its length, and draped high at the sides to form an oval drapery, and a

closely-fitted back, draped to form a bournous and a deep oval drapery, a fancy collar, a standing collar, and coat-sleeves being added.

What I claim as my invention, and desire to secure by Letters Patent, is—

The design for a lady's polonaise, as shown in the engraved prints accompanying this specification.
